(57) **CLAIM**

The ornamental design for a cargo pouch, as shown and described.

DESCRIPTION

FIG. 1 is a perspective elevational view of an ornamental design for a cargo pouch according to the present invention in extended configuration;

FIG. 2 is a front elevational view thereof;

FIG. 3 is a rear elevational view thereof;

FIG. 4 is a left side elevational view thereof, the opposite side being a mirror image thereof;

FIG. 5 is a perspective of the cargo pouch in a folded configuration; and,

FIG. 6 is a left side elevational view of the cargo pouch in folded configuration, the opposite side being a mirror image thereof.

The broken lines illustrate portions of the cargo pouch and form no part of the claimed design.
